(57) **CLAIM**

The ornamental design for a heater, as shown and described.

DESCRIPTION

FIG. 1 is a perspective view of the ornamental design for a heater.

FIG. 2 is a side view of the ornamental design for a heater; and,

FIG. 3 is an opposite side view of the ornamental design for a heater.

The broken lines showing in the Figures are environmental and form no part of the claimed design.

1 Claim, 3 Drawing Sheets

FIG. 2

FIG. 3
